Filed Apr. 8, 1968, Ser. No. 11,342

Term of patent 3½ years

Int. Cl. D8—03

U.S. Cl. D87—2

FIG. 1 is an exploded perspective view of a handbag lock embodying my new design.

FIG. 2 is a front elevational view of the handbag lock in the assembled condition, the opposite side being substantially flat and unornamented. The broken line showing of a handbag is for illustrative purposes.

FIG. 3 is a side elevational view thereof.

I claim:

The ornamental design for a handbag lock, substantially as shown and described.
